COOLING APPARATUS

Elo Carl Tanner, Springfield, Mass., assignor to Westinghouse Electric & Manufacturing Company, East Pittsburgh, Pa., a corporation of Pennsylvania

Application August 28, 1935, Serial No. 38,171

8 Claims. (Cl. 62—141)

My invention relates to liquid cooling apparatus, and particularly to a combined bottled beverage cooler and draft liquid cooler.

It is an object of my invention to provide a draft liquid cooler for a bottled beverage cooler which may be supplied as original equipment with the bottled beverage cooler, or may be utilized to convert existing bottled beverage coolers to combination bottled beverage coolers and draft liquid coolers.

It is another object of my invention to provide a draft liquid cooler for use in a refrigerated cabinet, wherein the draft liquid is available at an accessible portion of the exterior of the cabinet, which cooler, including a container for the liquid to be cooled, a faucet, and a pipe connection between the faucet and the container, is removable from the cabinet as a unit, without disconnecting the faucet or pipe connection.

It is a further object of my invention to provide a draft liquid cooler for a bottled beverage cabinet, in which heat is abstracted from the bottled beverage bath, and wherein the draft liquid cooler is partially immersed in the bath so that heat is also abstracted from the draft liquid.

It is still a further object of my invention to provide a draft liquid cooler from which heat may be abstracted by mechanical refrigeration, which draft cooler is readily removable from the cabinet containing the draft liquid cooler without disturbing the refrigerant connections of the refrigeration system.

These and other objects are effected by my invention as will be apparent from the following description and claims taken in connection with the accompanying drawings, forming a part of this application, in which:

Fig. 1 is a perspective view of a cabinet containing a bottled beverage cooler and a draft liquid cooler;

Fig. 2 is a sectional elevation of the cabinet shown in Fig. 1;

Fig. 3 is a bottom view of my draft liquid cooler; and,

Fig. 4 is a sectional view of the draft liquid cooler taken on line II—II of Fig. 3 when looking in the direction of the arrows.

Referring specifically to the drawings for a detailed description of my invention, Figs. 1 and 2 illustrate a cooling cabinet generally designated at 11. The cabinet 11 is divided into a machinery compartment 12 and a refrigerated compartment 13 by a heat insulated partition 10. A motor-compressor unit 14, a condensing element 15, and a distributing valve 16 are disposed in

the machinery compartment 12. A cooling element 17 is disposed in the refrigerated compartment 13. The refrigerated compartment 13 is provided with an upper access opening 18, a portion of which is covered by a hinged closure 19. The remainder of the access opening is covered by a removable supporting plate 21 for a draft liquid cooler generally designated at 22.

Referring to Figs. 2, 3, and 4, the draft liquid cooler 22 comprises a faucet 23 on the top of plate 21 connected to a supply of liquid by a conduit 24. The faucet is also connected by a conduit 25 to a coil or cooling vessel 26, which coil or cooling vessel is in turn connected through a conduit 28 to outlet 27 on the top of plate 21. A pressure regulating valve 29 is connected between the faucet 23 and coil 26 in the conduit 25. A drain conduit 31 is provided adjacent the outlet 27. The drain conduit 31 extends into a funnel shaped conduit 31a which catches drain water. A drain conduit 32 is attached to the funnel 31a and extends to the exterior of the cabinet 11.

The refrigerated compartment 13 is preferably filled with a sweet water bath, indicated at 30, which bath is cooled by the cooling element 17 of the refrigerating system. Bottled beverages are immersed in the bath 30 for cooling, access being obtained to the bottled beverages through the hinged closure member 19. The coil 26 is also immersed in the cooled sweet water bath 30 so that heat is abstracted from the draft liquid passing through the coil 26.

The draft liquid cooler 22 may be removed as a unit from the cabinet 11 by disconnecting only the supply conduit 24, and a suitable union 33 is provided for this purpose at the exterior of the cabinet 11. The draft liquid cooler 22 may be supplied with the cabinet 11 as original equipment, or bottled beverage cooler cabinets may be converted to combination bottled beverage and draft liquid coolers by providing a closure means 19 as shown in Figs. 1 and 2 and utilizing the supporting plate 21 to cover the remainder of the access opening 18. Since the draft liquid cooler 22 is a unitary assembly, all that is necessary to convert a bottled beverage cabinet into a combined bottled beverage and draft liquid cooler is to change the closure and provide supply and drain connections to the draft liquid cooler. Furthermore, since the draft liquid cooler is removable and replaceable as a unit, it is an easy matter to replace or repair the draft liquid cooler.

From the foregoing, it will be apparent that I have provided a bottled beverage cabinet which

may be provided with a novel draft liquid cooler at minimum expense, and which draft liquid cooler is removable and replaceable by merely making or breaking liquid supply connection. In 5 addition, the draft liquid is readily accessible exteriorly of the cabinet. No refrigerant or gas connections need be broken in removing or replacing the draft liquid cooler, and, therefore, the dangers of escaping refrigerant or loss of 10 charge from the refrigerating machine are avoided.

While I have shown my invention in but one form, it will be obvious to those skilled in the art that it is not so limited, but is susceptible of 15 various changes and modifications without departing from the spirit thereof, and I desire, therefore, that only such limitations shall be placed thereupon as are imposed by the prior art or as are specifically set forth in the appended 20 claims.

What I claim is:

1. In refrigeration apparatus, the combination of a beverage cabinet embodying a beverage storage compartment having an access opening there-in, closure means for said access opening, a cooling vessel for draft liquid inserted into said beverage storage compartment, means for abstracting heat from said beverage storage compartment and the beverage therein, said means being mounted 25 in said beverage compartment independently of said closure, a member supporting said draft liquid cooling vessel in said cabinet and forming a portion of said closure means, and a connection for conveying cooled liquid from said draft liquid 30 cooling vessel to an accessible portion at the exterior of said cabinet, said cooling vessel, supporting member and connection being removable from said cabinet sa a unit.

2. In a liquid cooler, the combination of an insulated cabinet embodying a compartment to be refrigerated, means for extracting heat from said compartment, a container for the liquid to be cooled disposed in said compartment, means for conveying liquid from said container to an accessible portion of the exterior of the cabinet, a liquid supply conduit for said container, means for detachably connecting the liquid supply conduit to said container, a drain for the liquid disposed adjacent the aforesaid accessible portion of the cabinet, and a liquid drain conduit extending exteriorly of said cabinet, said drain conduit being spaced from the drain for the liquid in a position to receive liquid from said drain, so that said container is removable as a unit from said cabinet upon disconnection of said supply conduit only.

3. In refrigeration apparatus, the combination of an insulated cabinet containing a chamber for a refrigerated liquid bath, means for abstracting heat from said bath, a removable cover for said cabinet, a cooling vessel for draft liquids immersed, at least, in part of said refrigerated bath, and draft liquid inlet and outlet connections for said cooling vessel extending through and attached to said cover, said cover and draft liquid cooling vessel being removable from said cabinet as a unitary structure by disconnecting the draft liquid inlet connection from said cooling vessel and without affecting the heat abstracting means.

4. In a liquid cooler, the combination of an insulated cabinet containing a chamber for a refrigerated liquid bath, a removable cover provided on the cabinet, a cooling coil disposed in said chamber and supported independently of

said cover for abstracting heat from said chamber, a cooling vessel for draft liquid inserted, at least, in part of said chamber, and inlet and outlet connections for said cooling vessel extending through and attached to said cover, said cover and draft liquid cooling vessel being removable from said cabinet as a unitary structure when the inlet connection to said draft liquid cooling vessel is disconnected, and without affecting said cooling coil.

5. In a liquid cooler, the combination of an insulated cabinet having a removable cover, a container for a liquid bath in said cabinet, a refrigerating system having connected thereto a cooling coil for abstracting heat from said container, said cooling coil being disposed in said liquid bath independently of said cover, a draft liquid cooling vessel attached to and depending from the cover and inserted, at least in part, in the refrigerated container, a draft liquid inlet 20 connection for said cooler extending through and attached to said cover, and a faucet for controlling the withdrawal of the draft liquid mounted on said cover and connected to said inlet connection and said cooler, said cover, faucet, and draft liquid 25 cooler being readily removable from the cabinet as a unit when said inlet connection is disconnected and without breaking the connections between the cooling coil and said refrigerating system.

6. In a liquid cooler, the combination of an insulated cabinet having a container for a liquid bath, a removable cover for said container, a draft liquid cooling vessel attached to and depending from the cover at least in part into said container, means mounted in the cabinet independently of said cover for abstracting heat from said container, and a faucet mounted on the cover and connected to said draft liquid cooling vessel for controlling the withdrawal of the draft liquid, 40 said cover, draft liquid cooling vessel, and faucet being readily removable from the cabinet as a unitary structure.

7. In refrigeration apparatus, the combination of a cabinet embodying a water-tight storage 45 compartment having an access opening in its top, closure means for said access opening, said storage compartment providing space for bottled beverage to be cooled, a draft liquid cooling vessel inserted in said storage compartment, means for abstracting heat from said storage compartment disposed within said storage compartment independently of said closure, a member for supporting said draft liquid cooling vessel, at least in part, in said storage compartment and forming a 50 portion of said closure means, said draft liquid cooling vessel and supporting member being removable from said cabinet as a unit.

8. In refrigeration apparatus, the combination of an insulated cabinet containing a chamber for a refrigerated liquid bath, means for abstracting heat from said bath, a removable wall in said cabinet, a cooling vessel for draft liquids immersed, at least, in part of said refrigerated bath, and draft liquid inlet and outlet connections for said cooling vessel extending through and attached to said movable wall, said removable wall and draft liquid cooling vessel being removable from said cabinet as a unitary structure without affecting the heat abstracting means by disconnecting the draft liquid inlet connection from said cooling vessel.

ELO CARL TANNER.
